(57) **CLAIM**

I claim the ornamental design for a cervical collar cover, as shown and described.

DESCRIPTION

FIG. 1 is a perspective view of a cervical collar cover showing my new design in use, the broken line showing of the head is for illustrative purposes only and forms no part of the claimed design.

FIG. 2 is an end elevation as viewed from the left in FIG. 4; FIG. 3 is an end elevation as viewed from the right in FIG. 4;

FIG. 4 is a front elevation of the cover of FIG. 1 in uncoiled condition;

FIG. 5 is a top edge view of the cover as viewed from the top in FIG. 4;

FIG. 6 is a bottom edge view of the cover as viewed from the top in FIG. 4; and,

FIG. 7 is a rear elevation of the cover as viewed by rotating FIG. 2 180 degrees about its horizontal, longitudinal axis.
